NONREFILLABLE BOTTLE

Rosto E. Colton, Chester Depot, Vt., assignor of
one-third to George X. Roberts, Chester, Vt.,
and one-third to John A. McGuire, Newton,
Mass.

Application January 8, 1934, Serial No. 705,785

1 Claim. (Cl. 215—22)

This invention relates to non-refillable bottles, and more particularly to attachments for bottles adapted to render the latter non-refillable.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is a fragmentary sectional view of a bottle in combination with the attachment of my invention which renders the bottle non-refillable.

Fig. 2 is a section taken on line 2—2 of Fig. 1.

Fig. 3 is a section taken on line 3—3 of Fig. 1; and

Fig. 4 is a fragmentary side view, partly in section, of a bottle in combination with the attachment of my invention, said attachment being shown mostly in section, and the bottle and said attachment being in position for pouring liquid from the bottle thru the attachment.

Referring to the drawing for a more detailed description thereof, numeral 5 indicates a bottle having a neck 6, the outer surface of which is provided with an annular groove 7. The device or attachment which renders the bottle non-refillable is indicated by the numeral 8 and comprises a tubular member 9 which is positioned over and around the neck of the bottle. The internal diameter of the tubular member 9 is slightly larger than the external diameter of the neck of the bottle, leaving a space between the neck and the tubular member which is filled thru a lateral aperture 10 in the wall of the tubular member with any suitable substance adapted to hold said tubular member to the neck of the bottle, said substance filling the annular groove 7 in the periphery of the bottle neck and also a groove 11 formed on the inner surface of said tubular member and positioned opposite the groove 7. A disc 12, having a central outlet aperture 13, is positioned on the top of the bottle neck and is held in place by a shoulder 14 formed in said tubular member. When the bottle is in the upright position the outlet aperture 13 is closed by a valve member 15 which rests on the disc 12, said valve member being herein illustrated as of cylindrical form. Said valve member is preferably of light weight and is held seated

on the disc 12, when the bottle is in upright position, by a weight 17 herein shown as a sphere. Said sphere is movable between the valve member 15 and a concave central member 18, which is integrally connected with the tubular member 9 by spaced radial arms 20. The spaces 21 between said radial arms 20 provide passageways for the flow of liquid thru the tubular member, that part of the tubular member between the lower surface of the member 21 and the disc 12 having spaced vertical ribs 22 providing therebetween passageways 23 for the flow of liquid thru that portion of the tubular member.

When the bottle is in a tilted position, as indicated in Fig. 3, the weight 17 moves into abutment against the concave member 18 and the valve member 15 moves from its seat on the disc 12, being guided by the ribs 22 mentioned above, the liquid from the bottle then being free to flow thru the aperture 13 of the disc 12, then successively thru the passageways 23 and 21 and out thru the orifice 25.

If an attempt is made to fill the bottle while it is in tilted position, as shown in Fig. 4, for example, the valve member 15 being of light weight, will be floated to a position against the disc 12, thereby closing the aperture 13 and prevent the bottle from being refilled.

What is claimed is:

The combination with a bottle of a device for rendering the bottle non-refillable, said device including a tubular member secured to the neck of the bottle, a disc across the mouth of the bottle and having an outlet aperture, a slidably valve element within said tubular member adapted to close the aperture in said disc when the bottle is in upright position and to open the aperture when the bottle is tilted to permit liquid to be poured from the bottle, and a free movable weight seated on said slidably element when the bottle is upright, said slidably element being sufficiently light to be floated against said disc when attempt is made to fill the bottle by introducing liquid into the tubular member with the bottle tilted to a position with its mouth down, said tubular member having an outlet orifice, a centrally located element within said tubular member, directly below the outlet orifice and spaced therefrom, spaced radial arms connecting said element to said tubular member and spaced guiding ribs formed internally on said tubular member and extending inwardly substantially to said valve element and weight and adapted to guide said valve and weight and extending downwardly from a level with the bottom of said element substantially to said disc.

ROSTO E. COLTON.
